UNITED STATES PATENT OFFICE

2,333,306

SUPPORTING DEVICE FOR INSTRUMENTS

Jacob Franz Fishter, Los Angeles, Calif., assignor
to American Eolex Company, New York, N. Y.,
a corporation of New York

Application February 2, 1942, Serial No. 429,254

9 Claims. (Cl. 248—183)

This invention relates generally to scientific and technical instruments such as cameras, telescopes, transits, levels, range finders, etc., and more particularly to an adjustable support or tripod head therefor.

An object of this invention is to provide a device structurally characterized by means enabling an instrument to be mounted on a tripod or other supporting structure for unrestricted panoramic adjustment throughout three hundred and sixty degrees, and tilting adjustment through an angle of at least ninety degrees to either side of a horizontal position, all in such manner that these adjustments can be effected concurrently or independently with the utmost smoothness and convenience, all while insuring that the instrument will be rigidly supported by the device in any position of adjustment.

Another object of the invention is to provide a tripod head embodying a locking means of novel construction for the tilting adjustment of the head, which when unlocked, insures freedom of movement without any looseness between the tiltable portion of the device and its pivotal mounting, and which when locked, positively prevents a change from any selected tilted position by the weight of the supported instrument, yet permits the operator to make fine tilting adjustments without unlocking the locking means.

A further object of the invention is to provide a tripod head of the above described character which is simple, rugged and compact in construction; is light in weight; is operable to effect panoramic and tilting movements through the medium of gear mechanisms insuring smooth, positive and dependable operation indefinitely.

With these and other objects in view, the invention resides in the combinations, arrangements and functional relationships of elements as set forth in the following specification and particularly pointed out in the appended claims.

In the accompanying drawings,

Figure 1 is a plan view of the supporting device for instruments embodying this invention;

Figure 2 is a view of the device in side elevation and partly in section, with a portion broken away to expose internal structure;

Figure 3 is a vertical sectional view taken on the line 3—3 of Figure 2;

Figure 4 is a horizontal sectional view taken on the line 4—4 of Figure 3;

Figure 5 is an enlarged fragmentary vertical sectional view illustrating a locking mechanism embodied in the invention;

Figure 6 and Figure 7 are fragmentary sec-

tional views taken respectively on the lines 6—6 and 7—7 of Figures 5 and 4 respectively.

Referring specifically to the drawings, the invention in its illustrated embodiment comprises a stationary support or base 10 which constitutes a gear housing and has its bottom wall 11 provided with a vertical bore 12 screw threaded to receive the threaded shank of the standard instrument attaching screw of a tripod (not shown), to detachably and rigidly secure the head thereon. The bore 12 extends into a post 13 rising from the bottom wall 11 centrally of a chamber 14 defined by an upstanding flange 15.

Rotatably mounted on the post 13 for panoramic or "panning" movements, is an element 16, and pivotally mounted on the element 16 for tilting movements about an axis at a right angle to and intersecting the axis of the post 13, is a second element 17 on which latter a camera or other instrument is adapted to be supported.

The element 16 has a disk or cover portion 20 from which centrally depends a bearing sleeve 21 rotatably mounted on the post 13 and confined against upward displacement therefrom by a headed screw 22 threaded into the post and extending freely through a non-circular opening in a washer 23 receiving a complementarily shaped upper portion 24 of the post. The washer 23 bears against an arched resilient plate 25 having an opening freely receiving the diameter of the post 13, and stressed by the screw 22 sufficiently to force and yieldingly maintain the under surface of the disk portion 20 in friction sealing contact with the upper edge of the base flange 15, whereby to frictionally retain the element 16 in any rotatably adjusted position.

Depending from the disk portion 20 into the chamber 14 concentrically of the post 13, is an annular flange, the periphery of which is provided with suitable gear teeth 30 to form a driven gear 31, which, specifically, is a worm wheel. Constantly meshing with the gear 31 is a driving gear 32 in the form of a worm disposed in a pocket 34 of the base 10 communicating with the chamber 14.

The worm 32 is provided with a non-circular bore 35 slidably receiving the non-circular portion 36 of a drive shaft 37 to provide a driving connection between the worm and shaft. The shaft 37 is journaled in bearings 38 and 39 in the base 10 and is reduced in diameter at one side wall of the pocket 34 to provide an annular groove 40 into which projects a U-shaped retainer 41 which locks the shaft against axial displacement in the base, permits unrestricted

rotation of the shaft. The retainer 41 fits the pocket 34 and is confined against displacement from the groove 40 by a cover plate 42 which closes the pocket 34 and is secured in place by screws 43, all of which is clearly shown in Figures 4 and 7. A crank handle 44 is fixed to the outer end of the shaft 37 to enable the latter to be conveniently rotated to impart "panning" movement to the element 16 on the base 10.

Rising from the base 10 at opposite sides of the plate 25 are spaced vertical brackets 50 and 50a having aligned openings receiving a fixed pivot pin 51 on which is mounted for the aforesaid movements, the element 17. The upper face of the element 17 is formed with a recess 52 freely receiving the knurled knob 53 of an attaching screw 54 projecting freely through an opening 55 in a keeper plate 56 secured to the element 17 by screws 57 (Figure 1). By means of the screw 54, a camera or other instrument (not shown), provided on its under side with a threaded socket, can be detachably secured rigidly on the element 17. The peripheral portion of the element 17 is provided with teeth to form a segmental spur gear 60 with which constantly meshes a driving pinion gear 61 fixed to a shaft 62 one end of which is reduced in diameter to form a journal 63 rotatably mounted in the bracket 50.

The other end of the shaft 62 is also reduced in diameter to receive a bearing sleeve 64 closely fitting an opening in the bracket 50a, and being slightly larger in diameter than the gear 61 so as to permit installation of the latter between the two brackets.

At the outer side of the bearing sleeve 64, the shaft 62 is further reduced in diameter to form an annular groove 65 receiving a bifurcated retainer 66 secured to the bracket 50a by a screw 67, and co-acting therewith to prevent axial displacement of the shaft 62 relative to the brackets. Fixed to the outer end of the shaft 62 is an operating knob 68, by rotation of which, tilting movement of the element 17, and hence of the instrument supported on the latter, can be smoothly effected as desired in one direction or the other.

The element 17 is adapted to be locked in any selected adjusted position relative to the panoramically movable element 16 by means of a locking mechanism which comprises a friction locking member 70 in the form of a body having a cylindrical head 71 from which co-axially projects a cylindrical guide shank 72. The head 71 is mounted in an opening 73 in the bracket 50a, and the shank 72 projects into an arcuate slot 74 formed in the tilting element 17 concentrically of the axis of the pivot pin 51 as clearly shown in Figure 3.

An operating member includes a shaft 75 having one threaded end 76 screwed into a threaded bore 77 in the bracket 50, and extending through an axial bore 78 in the locking member 70. The other and non-circular end 79 of the shaft 75 is disposed beyond the outer side of the bracket 50a and has secured thereon by a headed screw 80, the hub 81 of a lever 82.

Surrounding the shaft 75 and disposed in a pocket 83 in the locking member 70 is a coil spring 84 which bears against the end wall 85 of the pocket and against the confronting face of the hub 81, to urge the locking member axially on the shaft. A washer 86 of fibre or other friction creating material freely receives the shank 72 and is interposed between the annular transverse shoulder 87 of the head 71 and the con-

fronting side face of the tilting element 17 for co-action therewith in normally holding the locking member 70 firmly by taking up any clearance between the element and the brackets 50 and 50a. Upon actuating the lever 82 in a direction to cause the shaft to be advanced axially by its threads 76, the hub 81 of the lever will push against the head 71 of the locking member and thus cause the head to co-act with the washer 86 in setting up sufficient friction to hold the tilting element 17 in any selected position of adjustment with such security that accidental displacement of the tilting element incident to the weight and/or position of the instrument thereon will be positively prevented.

It will be clear that in the unlocked position of the lever 82, the spring 84 will yieldingly function to take up any necessary working clearance between the parts and form a brake upon the movement of the element 17, and that in the locked position of the lever 82, the yielding force of the spring is added to by the unyielding force imposed by the axial feeding of the shaft 75, so as to securely bind the tilting element in its adjusted position.

It will be manifest that in the operation of the invention, the element 16 can be rotated throughout three hundred and sixty degrees in one direction or the other with the utmost ease and smoothness of movement; that the element 17 can be tilted from a horizontal position in one direction or the other through an angle of ninety degrees; and that with the crank handle 44 at the right hand of the operator and the knob 68 at the left hand or one hundred eighty degrees from the handle, the elements 16 and 17 can be concurrently or independently moved manually in whatever direction desired to maintain the instrument trained on a subject. Furthermore, by a simple actuation of the lever 82 with the left hand thumb and forefinger, towards and away from the operator, the tiltable element 16 can be locked or released at will, all while insuring that lost motion between the working parts will have no adverse effect upon the camera which will be rigidly supported by the head in any position of adjustment thereof.

It will also be understood that although the tiltable element 17 can be securely locked against displacement by the lever 82, this element can still be adjusted by actuating the knob 68 without unlocking the lever 82, thus enabling a very fine micrometer-like adjustment to be made in opposition to the strong resistance offered by the firm frictional gripping of the element between the bracket 50 and the washer 86.

I claim:

1. In a supporting device for instruments, a base having an upstanding flange defining an upwardly opening chamber; a post in the chamber; two elements pivotally connected for relative tilting movements, with one of the elements adapted to support an instrument; the other of the elements having a cover portion closing the top of said chamber, and provided with a depending bearing sleeve receiving said post to mount said other element thereon for panoramic movement; means co-acting with said post and cover portion to confine said other element against upward axial displacement from said post and to maintain said cover portion in sealing contact with said flange; the base having spaced bearings providing a pocket therebetween communicating with said chamber; a drive shaft journaled in said bearings and having a non-

circular portion in said pocket; a driving gear insertable into said pocket and having a non-circular bore receiving said non-circular portion of the shaft to provide a driving connection between the latter and gear, yet permitting insertion and withdrawal of the shaft from the bearings; the shaft having an annular groove in said pocket; a retainer confined in said pocket and projecting into said annular groove to secure the shaft against axial displacement; and a driven gear depending from said cover portion into said chamber, and meshing with the driving gear.

2. In a supporting device for instruments, a base having an upwardly opening chamber and spaced bearings defining a pocket therebetween communicating laterally with said chamber; two elements pivotally connected for relative tilting movements, with one of the elements adapted to support an instrument; means mounting the other of said elements on the base for panoramical movement and to close the top of said chamber; a drive shaft insertable axially into said bearings; a driving gear insertable into said pocket; means mounting said gear on the drive shaft for rotation thereby; a retainer co-acting with said shaft to prevent axial displacement of the latter from said bearings; a removable closure for said pocket confining the retainer against displacement; and a driven gear on said other element disposed in the chamber and meshing with the driving gear.

3. In a supporting device for instruments, a base; a plurality of elements, one of which is mounted on the base for panoramical movement, and the other of which is adapted to support an instrument; said one element having spaced brackets between which the other element is interposed; means pivotally mounting said other element from the brackets for tilting adjustment; means co-acting with the elements, by which actuation of said other element can be effected; a locking member mounted in one of said brackets at a location concentrically of said pivotal mounting for movement towards and away from a lateral surface of said other element; means co-acting with the locking member to yieldingly urge the latter into sufficient frictional engagement with said lateral surface of the other element to restrain same against tilting movement for adjustment freely by said actuating means; and an operating member extending through said locking member and threaded into one of said brackets; the operating member having means co-actable with the locking member in response to axial feeding of the operating member when rotated in one direction, to positively advance the locking member into firm engagement with said lateral surface of said other element, and securely maintain the latter against displacement.

4. In a supporting device for instruments, a base; a plurality of elements, one of which is mounted on the base for panoramical movement, and the other of which is adapted to support an instrument; said one element having spaced brackets between which the other element is interposed; means pivotally mounting said other element from the brackets for tilting adjustment; a shaft journaled in said brackets; a driving gear fixed to said shaft; a driven gear on said other element, meshing with the driving gear for tilting adjustment of said other element; said other element having an arcuate slot concentrically related to the axis of said piv-

otal mounting; a locking member having a head mounted in one of said brackets and a shank projecting into said slot; an operating shaft projecting through said locking member and slot and threaded into the other of said brackets; a lever having a hub fixed to the operating shaft and bearing against said head; and a spring in said locking member co-acting with said hub and the locking member to urge the latter axially; said head and shank of the locking member co-acting to define a transverse shoulder frictionally engageable with said other element under the urging action of said spring or by axial feeding of said operating shaft when rotated in one direction.

5. In a supporting device for instruments, a base having an upstanding flange defining an upwardly opening chamber; two elements, one of which is provided with spaced brackets between which the other element is pivotally mounted for tilting movements; an operating shaft mounted in said brackets and having a gear thereon; a gear on said other element meshing with the first gear; said one of the elements having a cover portion closing the top of said chamber, said base and cover member being provided with means to mount said one of the elements on the base for panoramical movement; a driving gear rotatably mounted in the base; a driven gear on said cover portion, meshing with the driving gear in said chamber; a locking member mounted in one of said brackets at a location concentrically of said pivotal mounting for movement towards and away from a lateral surface of said other element; means co-acting with the locking member to yieldingly urge the latter into sufficient frictional engagement with said lateral surface to restrain said other element against tilting movement for adjustment freely upon rotation of said first gear; and means co-acting with the locking member to positively move same to a locking position with respect to said other element so as to maintain the latter securely in any selected adjusted position.

6. In a supporting device for instruments, a base having an upstanding flange defining an upwardly opening chamber; two elements, one of which is provided with spaced brackets between which the other element is pivotally mounted for tilting movement; said one of the elements having a cover portion closing the top of said chamber, and provided with means co-acting with the base to mount said one of the elements on the base for panoramical movement; a driving gear rotatably mounted in the base; a driven gear on said cover portion, meshing with the driving gear in said chamber; said other element having an arcuate slot concentrically related to the axis of said pivotal mounting; a locking member having a head mounted in one of said brackets and a shank projecting into said slot; an operating shaft projecting through said locking member and slot, and threaded into the other of said brackets; a lever having a hub fixed to the operating shaft and bearing against said head; and a spring in said locking member co-acting with said hub and the locking member to urge the latter axially; said head and shank of the locking member co-acting to define a transverse shoulder frictionally engageable with said other element under the urging action of said spring or by axial feeding of said operating shaft when rotated in one direction.

7. In a supporting device for instruments, a

base having an upstanding flange defining an upwardly opening chamber; a post in the chamber; two elements pivotally connected for relative tilting movements, with one of the elements adapted to support an instrument; the other of the elements having a cover portion closing the top of said chamber; means rotatably mounting said other element on the base for panoramical movement; the base having spaced bearings providing a pocket therebetween communicating with said chamber; a drive shaft journaled in said bearings; a driving gear insertable into said pocket; means mounting said gear on said shaft in the pocket for rotation by the shaft, yet permitting withdrawal of the shaft axially from the gear and said bearings; means co-acting with the shaft to confine the latter against axial displacement from said gear; and a driven gear depending from said cover portion into said chamber and meshing with the driving gear.

8. In a supporting device for instruments; a base having an upstanding flange defining an upwardly opening chamber; two elements pivotally connected for relative tilting movements, with one of the elements adapted to support an instrument; the other of the elements having a cover portion closing the top of said chamber; a driven gear depending from said cover portion into said chamber for rotating the other element for panoramical movement; the base having spaced bearings providing a pocket therebetween

communicating with said chamber; a drive shaft journaled in said bearings and having a non-circular portion in said pocket; a driving gear meshing with the driven gear and receivable in said pocket and having a non-circular bore receiving said non-circular portion of the shaft to provide a driving connection between the latter and the driving gear, yet permitting insertion and withdrawal of the shaft from the bearings; the shaft having an annular groove in said pocket; and a retainer confined in said pocket and projecting into said annular groove to secure the shaft against axial displacement.

9. In a supporting device for instruments; a base; two elements pivotally connected for relative tilting movements, with one of the elements adapted to support an instrument, and the other element being rotatably mounted on the base for panoramical movement; the base having spaced bearings providing a pocket therebetween; a drive shaft journaled in said bearings; a driving gear insertable into said pocket; means mounting said gear on said shaft in the pocket for rotation by the shaft, yet permitting withdrawal of the shaft axially from the gear and said bearings; means coacting with the shaft to confine the latter against axial displacement from said gear; and a driven gear on the other element meshing with the driving gear.
